Mills Company, Rothschild, Wis., a corpora-
tion of Wisconsin

Application July 22, 1938, Serial No. 220,684

7 Claims. (Cl. 229—51)

This invention relates to a carton, and particularly to a carton made of fibrous material for packaging ice cream and other frozen comestibles.

5 The present invention contemplates a carton construction provided with means for readily opening the same so as to make the contents accessible without any attendant peeling or tearing of the fibrous material from which the carton 10 is made.

An object of the invention is to provide a carton for ice cream and the like which when opened may be spread out flat so as to completely expose the frozen contents of the package 5 for slicing or removal as a whole.

A further object of the invention is to provide a carton for ice cream packaging which is formed from a single blank of board scored and folded to provide a carton with interlocking ends so 20 arranged and associated with respect to the cover that when the cover is opened the whole carton will open exposing the contents for slicing or removal as a unit.

A still further object of the invention is to 25 provide a carton formed from a single blank of thin board material scored and folded in a box form and provided with a flap which is glued to close the carton and which can be readily grasped and torn off to expose the carton for removal of its contents.

Further advantages and details will be apparent from the accompanying drawing in which:

Figure 1 is a plan view of the blank from which the carton is made.

35 Figure 2 is a perspective view of the blank in folded and unsealed condition,

Figure 3 is a front view of the sealed carton,

Figure 4 is a sectional view taken on line 4—4 of Figure 1, and

40 Figure 5 is a side view of the sealed carton illustrating the grasping tab in bent position.

Referring to the drawing, the carton is made from a single blank of paper board which is preferably impregnated or coated with paraffin 45 wax. The blank is scored along lines 1, 2, 3, and 4 to provide a front wall 10, a cover 13, rear wall 12 and bottom wall 11.

The front wall 10 is provided with free end flaps 15 and 16 separated from the adjacent flaps 50 by slit lines 6 and 7. Flap 15 is provided with a tongue portion 24. Flap 16 is slit along lines 23 and 23'. Rear wall 12 is similarly provided with end flaps 19 and 20 separated from adjacent flaps by slits 26 and 28, and 25 and 27 respective-

ly. Flap 19 is provided with slits 23 and 23', and flap 20 is provided with a tongue 24.

The cover 13 is provided with inner end flaps 21 and 22. The bottom 11 is provided with inner end flaps 17 and 18. One end of the carton is adapted to be closed by overlapping inner end flaps 18 and 22, and interlocking thereover outer flaps 16 and 20 by inserting tongue 24 through slit 23'. The other end of the carton is adapted to be closed similarly by folding inner flaps 17 10 and 21 in overlapping relation and then locking outer overlapped flaps 15 and 19 by means of tongue 24 extending through slit 23'.

The cover 13 has a flap extension consisting of adjacent panels 14, 35, 36 and 37 formed by 15 score lines 30, 40 and 41. Panel 14, designated as extension panel, is hinged to the cover along score line 4. Panel 35, designated as outer grasping panel and panel 36 as inner grasping panel, are of substantially the same width. Panel 20 37 will be referred to as the glue panel.

Score lines 40 and 41 are partially cut through the blank as shown in Figure 4. Score lines 39 are provided at each end of panel 35 and intersecting score lines 38 are provided at the ends 25 of panel 36 as shown in Figure 1 for a purpose to be explained later.

In making the carton for use, the flap extension is folded back on itself so that panels 36 30 and 37 are folded over on panels 14 and 35 along score line 40. The folded-over abutting faces of grasping panels 35 and 36 are preferably glued together by adhesive 55. Glue panel 37 is then glued by adhesive 50 to the upper edge of the front wall 10 as shown in Figures 3 and 4. 35

The sides of panels 14, 35, 36 and 37 constituting the extension on cover 13 are preferably sloped toward each other as shown in Figure 1 so that the grasping panels will be spaced away slightly from the ends of the carton as shown 40 in Figure 3.

The cartons are shipped by the carton manufacturer to the carton user in knocked-down flat condition with the extension on cover 13 folded and glued to the front wall 10 as previously described. 45

In use the carton is folded up into its rectangular condition as shown in Figure 5. One end of the carton is closed by means of the end flaps previously described and ice cream or other 50 comestible to be frozen therein is introduced at the other open end. After being filled this end is closed and the carton transferred to the hardening room. The front of the carton will have the appearance shown in Figure 3.

When the consumer is ready to use the contents within the carton both ends of the carton are first opened by disengaging the interlocked outer flaps 16 and 20, and 15 and 19 at each end. 5 The grasping panels 35 and 36 are then seized by the fingers as shown in Figure 5 and pulled back so as to tear the glued portion of panel 37 away from the front wall 10. The contents of the carton will then be left freely exposed resting 10 upon the bottom 11 of the carton.

The construction of the extension panels and score lines as previously described facilitates the ready grasping of the grasping panels and tearing open of the carton without peeling the fibrous 15 stock material. Score lines 30 and 41 facilitate bending up of the grasping panels as shown in Figure 5. Score lines 38 and 39 also provide corner grasping portions 60 which can be first grasped and folded up thereby facilitating grasping 20 of the grasping panels. There will be no peeling of the carton blank on the inside of the carton because the fibers cannot peel beyond the upper outer edge of the front wall 10 when the carton is opened as the fibers on the inner face 25 of the sealing flap are discontinuous with the fibers of the overlapped portion of the front wall. The partially cut score line 40 also permits panels 35 and 36 to be folded compactly without bulging at the fold thereby giving a compact and neat 30 appearance to the grasping panels.

The carton construction thus provides a carton made from a single blank of paper board having a cover provided with an integral extending sealing flap which serves to seal the carton. 35 This flap is formed into panels 14, 35, 36 and 37 and is folded and secured to itself as previously explained so as to provide inner and outer flap portions. The inner face of the sealing flap is adhered to an overlapped portion of the adjacent 40 wall by means of glue applied adjacent the inner edge of the sealing flap. The score lines 30 and 41 on the sealing flap provide hinged grasping portions for tearing open the sealing flap. Corner grasping portions are also provided by suitable score lines to facilitate seizing of 45 the grasping panels.

It is to be understood that variations and modifications of the specific embodiment disclosed are intended to be included within the scope of 50 the appended claims.

We claim:

1. A carton formed from a paper blank scored and cut to form a bottom, front and back walls and a cover, end flaps on said walls for closing 55 the ends of the carton, an extension on the free edge of the cover adapted to be folded over the front wall in overlapping relation and adhered thereto, said extension comprising a plurality of adjacent panels, the free end panel being adapted 60 to be glued to the front wall and the intermediate panels providing grasping means for tearing said end panel free without peeling a fibrous layer from the inner surface of the cover panel.

2. A paper carton formed from a single blank 65 cut and scored to define side and bottom walls and a closure wall for the carton, one of said walls having a hinged sealing flap integrally extending therefrom and overlapping an adjacent wall portion, said sealing flap comprising 70 a glue panel, an inner grasping panel, an outer grasping panel and an extension panel, said sealing flap being folded back on itself and secured together, the glue panel being glued to the overlapped portion of the adjacent wall, and the

superposed inner and outer grasping panels providing a grasping portion for tearing the flap from the overlapped wall.

3. A carton made from paper board having a cover provided with an integral extending flap 5 which is folded back on itself and the folded portions secured together adjacent the line of fold, the folded flap being scored to provide a hinged grasping panel adjacent its free end, the flap being secured to a wall of the carton by 10 gluing the folded-back portion only adjacent its inner edge to the wall so that the carton may be opened without peeling a fibrous layer from the inner surface of the carton.

4. A carton made from a single blank of paper 15 board, having a cover provided with an integral extending flap, said flap being folded back on itself along a partially cut fold line, the portions of the flap adjacent said score line being secured together, a partially cut score line on 20 the folded back portion of the flap spaced from the said fold line, a score line on the exposed flap portion spaced from the said fold line a distance substantially the same as the score line on the folded-back portion of the flap, the exposed portion of the folded-back flap being glued adjacent 25 its inner edge to an overlapped wall so that the carton may be opened without peeling the inner fibrous layers of the carton.

5. A carton made from a single blank of paper 30 board having a cover provided with an integral extending flap, said flap being folded on itself along a fold line and secured to itself adjacent 35 said fold line thereby providing an inner and outer flap portion, said flap portions being provided with score lines spaced substantially the same distance from the said fold line to form hinged inner and outer grasping panels for the flap, and the exposed surface of said inner flap portion being glued adjacent its inner edge to 40 an overlapped wall so that the carton may be opened without peeling the inner fibrous layers of the carton.

6. A carton made from a single blank of paper 45 board having a cover provided with an integral extending flap, said flap being folded on itself along a fold line and secured to itself adjacent 50 said fold line thereby providing an inner and outer flap portion, said flap portions being provided with score lines spaced substantially the same distance from the said fold line to form hinged inner and outer grasping panels for the flap, score lines provided on said grasping portions to provide corner grasping portions, and the exposed surface of said inner flap portion 55 being glued adjacent its inner edge to an overlapped wall so that the carton may be opened without peeling the inner fibrous layers of the carton.

7. A carton made from a single blank of paper 60 board, said carton having a cover provided with an integral extending flap which is folded back on itself and the folded portions secured together, score lines adjacent the corner portions 65 of said folded flap to provide hinged finger-grasping portions, the said flap being secured to a wall of the carton by gluing the folded-back portion only adjacent its inner edge to the wall whereby the carton may be opened without peeling 70 the inner fibrous layer.
